UNITED STATES PATENT OFFICE.

CHARLES W. YOUNG, OF OMAHA, NEBRASKA.

FIREPROOF BUILDING CONSTRUCTION.

1,202,951.

Specification of Letters Patent. Patented Oct. 31, 1916.

Application filed May 1, 1916. Serial No. 94,615.

To all whom it may concern:

Be it known that I, CHARLES W. YOUNG, a citizen of the United States, residing at Omaha, in the county of Douglas and State 5 of Nebraska, have invented certain new and useful Improvements in Fireproof Building Construction, of which the following is a specification.

This invention relates to an improvement 10 in a fire proof construction for the walls and floors.

One of the objects of the invention is to employ such a construction that floors and partition walls, including door bucks, may 15 be more quickly built than ordinary after the concrete or tile substructure for the floor has been molded or completed.

Another object is to provide an intermediate, fire-proof filler which will support 20 the wood floor strips uniformly and will provide compartments operating to advantage to prevent fire from spreading, will tend to "deaden" sounds or vibration incident to the use of wood floors, will not be injured by the 25 expansive force of heat and will provide a firm support for the door bucks.

Still another object is to provide such a construction that floors and partitions of fire 30 proof buildings may be more conveniently and economically built than ordinary, and that the parts employed, while discharging all required functions, may be few and simple.

In the drawing which illustrates the improvement, Figure 1 is a perspective view 35 showing parts of a floor, partitions and a door buck, embodying the invention, parts being broken away and in section. Fig. 2 is a view in side elevation of one of the fire-proof 40 supporting strips employed. Figs. 3 and 4 illustrate parts of partition walls in transverse section, showing facility for the mounting of base boards and picture molding by use of the fire proof strips with which the 45 partitions are provided.

For the purposes mentioned, fire-proof 50 supporting strips 5, best shown in Fig. 2, are employed, these being rectangular in cross-section and of any suitable length, width or thickness, as may be required. Each consists 55 of a wood core 6 into which nails may be driven or in which screws may be secured, and thereby operate as nailing-strips when laid in a wall for supporting the various kinds of interior finishings, as the base boards, one of which is indicated at 7 in Fig.

3, or the picture molding 8 shown in Fig. 4, or the floor strips 9 shown in Fig. 1. In order that said members 5 may be rectilinear they are formed in molds. The wood cores 6, 60 which are first thoroughly water proofed, are then immersed in a mixture of plaster of Paris and water. They are then wrapped with hemp, jute, cloth or light wire-cloth to provide an intermediate cover or layer 10, 65 the outer surface of which is also coated with the mixture, and a non-conducting envelop or jacket 11 is then provided of any suitable thickness, consisting of adhesive material with which a flexible filler has been mixed, 70 such as hemp, jute, sisal or a limited quantity of excelsior or saw dust, the adhesive material mentioned for said jacket consisting of gypsum plaster, gypsate, plaster of Paris or Portland cement. The fire-proof supporting 75 strips thus provided are used for all of the purposes herein to be described, and they are portable and convenient in use, will not shrink, and resist the action of fire to advantage.

In the construction of fire proof buildings there is generally provided a fire proof substructure 12 either of concrete or tile, upon which the floor and partitions are supported. To provide a suitable support for the floor 85 strips 9, a single reticulated layer is deposited on the base 12, consisting of widely spaced, relatively narrow, adhesive strips, beds or parts, indicated respectively at 13 and 13', the parts 13 being disposed parallel with 90 reference to each other and the parts 13' being disposed transversely with reference to the parts 13, the ingredients and proportions employed being two parts, in bulk, of gypsum plaster and three parts of clean, 95 coarse sand, these being mixed with water to make a semi-plastic mortar which will readily adhere to the base 12. Upon each parallel part 13 of said reticulated layer is disposed one of the fire-proof supporting strips mentioned, these being designated, for convenience, at 5^a, and on account of the construction as described, they will adhere to the parallel parts 13 of the reticulated layer.

At 5^b are indicated fire-proof cross-strips, 105 these being disposed on the transverse parts 13' of the reticulated layer. The comparatively short strips 5^b are produced, generally by sawing the strips 5 into suitable lengths or sections, and on that account, and to the 110 end that the wood cores 6 will be covered, a filler 14 of the adhesive mortar is placed

between the ends of the sections 5^b and the sides of the supporting-strips 5^a, so that the ends of the wood cores of these sections will not be exposed to the action of fire.

As thus described, numerous compartments 15 having imperforate walls and practically of uniform area are provided immediately below the floor strips, tending to prevent spreading of fire; the supporting-strips 5^a and supporting-strips or sections 5^b also, by this arrangement may be disposed in a plane to provide a uniform support for the floor strips, contact of the floor strips with the base 12 will be prevented and the cores 6 will be protected from the corrosive action of the base 12 if said base is constructed of concrete, the cement used in the concrete generally causing injury to wood if remaining in contact therewith a considerable period of time.

In the building of fire-proof partitions all wood may be eliminated except the wood cores 6 of the strips 5. As shown in the drawing, strips 5^c may be used in the partitions, each having any desired length or thickness, the width preferably being substantially the same as the wall tiles 16.

For rectangular door bucks 17, I provide a base consisting of a strip 5^d, other strips 30 respectively indicated at 5^e and 5^f being employed for the sides and top of the door buck, these parts, being secured together, as required, by keepers 18, and suitable tie-plates 19 being used for connecting the sides 35 of the door buck to the tiles. The strip 5^d or base of the door buck is placed upon the comparatively wide part 13" of the rectilinear layer above mentioned and the tiles for the partition abut upon the side strips 40 5^e, a pair of parallel strips 5^g being employed and disposed at the sides of the base 5^d which provides a firm support against 45 side movements of the door buck, and which as shown in Fig. 1, support the ends of the floor strips 9, all of said strips for the door buck and the parallel strips 5^g being of the same material and constructed in the same manner as the strip heretofore particularly described, and shown in Fig. 2. The door buck provides a fire-proof construction for 50 all door openings, and since the fire-proof strips therefor have an adequate width, they provide suitable supports to which other parts may be conveniently secured.

Among some of the advantages to be derived by use of the invention, it may be stated that the floors and partitions, including door bucks, may be quickly built or placed in position as soon as the base 12 for 55 the floors have been constructed, all parts except the floor strips 9 being fire proof and protected from any injurious action of a concrete base, and the parts being few, may be economical in construction.

Having fully described my invention,

what I claim and desire to secure by Letters Patent is,—

1. Devices for the purpose described, comprising, in combination with a floor base and floor boards, a single, reticulated, adhesive layer on said base consisting of parallel parts and transverse parts, imperforate supporting strips formed rectangular in cross-section and disposed on the parallel parts of said layer, secondary imperforate supporting strips formed rectangular in cross-section and disposed on the transverse parts of said layer to coöperate with the first named strips for sustaining the floor boards and to form a plurality of compartments intermediate the floor boards and floor base. 70 75 80

2. Devices for the purpose described, comprising, in combination with a floor base, a single, reticulated, adhesive layer on said base consisting of parallel parts and transverse parts, a plurality of imperforate supporting-strips formed rectangular in cross-section and disposed on the parallel parts of said layer, a plurality of secondary imperforate supporting-strips formed rectangular in cross-section each being disposed on a transverse part of said layer with each of its ends adjacent to the side of a first named supporting-strip, adhesive fillers between the ends of the secondary supporting-strips and the first named supporting-strips, each of the first named supporting strips and secondary supporting strips consisting of an elongated wood core circumscribed by a flexible jacket and a second jacket of non-combustible material circumscribing said first named jacket. 90 95 100 105

3. Devices for the purpose described, comprising, in combination with a floor base and the floor boards, a single reticulated, adhesive layer on said base having parallel parts and transverse parts and consisting in bulk substantially of two parts of gypsum plaster and three parts of sand mixed with water to form a semi-plastic mass, a plurality of rectilinear supporting-strips disposed on the parallel parts of said reticulated layer, secondary supporting-strips disposed on the transverse parts of said layer arranged to coöperate with the first named supporting-strips for sustaining the floor boards and to form a plurality of compartments intermediate said floor boards and floor base, each supporting-strip consisting of a fibrous, elongated core circumscribed by a flexible jacket, and a second jacket of adhesive, non-combustible material circumscribing said first named jacket. 110 115 120

4. Devices for the purpose described, comprising, in combination with a floor base, an adhesive bed thereon, a rectangular door buck having its base, top and side members composed of connected strips substantially rectangular in cross-section and adapted to be disposed upright with its base engaging 125 130

said adhesive bed, each of said strips consisting of an elongated core of fibrous material circumscribed by a flexible wrapper and a jacket of adhesive material circum-
5 scribing said flexible wrapper.

5. Devices for the purpose described, comprising, in combination with a floor base and the floor boards, a single reticulated, adhesive layer on said base having parallel
10 parts and transverse parts, a pair of parallel strips disposed on one of the parallel parts of the reticulated layer, an upright rectangular door buck consisting of connected strips and having its base disposed
15 between and in engagement with said pair of parallel strips, and a plurality of strips for sustaining the floor boards, each being disposed on a part of the reticulated layer, each of said strips consisting of a fibrous
20 elongated core circumscribed by a flexible jacket and a second jacket of adhesive non-combustible material circumscribing said flexible jacket.

6. Devices for the purpose described, comprising, in combination with a floor base and the floor boards, a plurality of supporting strips, each consisting of an elongated, rectilinear wood core circumscribed by a
25 flexible jacket and a second jacket of adhesive non-combustible material circumscribing the first named jacket, said sup-
30

porting-strips being disposed in angular relation with reference to each other and adhesively connected with said floor base for sustaining the floor boards and to provide compartments substantially rectangular in plan between the floor boards and said floor base. 25

7. Devices for the purpose described, comprising, in combination with a floor base, 40 an attenuated adhesive bed thereon, a rectangular door buck having its base, top and side members composed of connected rectilinear strips and disposed upright with its base engaging said adhesive bed, a pair 45 of parallel, horizontal supporting-strips disposed on said adhesive bed in engagement with the base and side members of the door buck, each of the parallel, horizontal supporting-strips and the strips for the base, 50 top and side members of said door buck consisting of an elongated, fibrous core circumscribed by a flexible jacket and a second jacket of adhesive non-combustible material 55 circumscribing said first named jacket.

In testimony whereof, I have affixed my signature in presence of two witnesses.

CHARLES W. YOUNG.
